UNITED STATES PATENT OFFICE.

GEORGE SEYMOUR, OF BOONE, IOWA.

IMPROVEMENT IN WASHING-MACHINES.

Specification forming part of Letters Patent No. 137,151, dated March 25, 1873.

To all whom it may concern:

Be it known that I, GEORGE SEYMOUR, of Boone, in the county of Boone and State of Iowa, have invented a new and useful Improvement in Washing-Machine, of which the following is a specification:

Figure 1 is a top view of my improved washing-machine. Fig. 2 is a detail vertical cross-section of the same taken through the line x - x , Fig. 1. Fig. 3 is a detail side view of one of the bearings for the rollers, showing the pair in position. Fig. 4 is an end view of one of the stationary rubbers.

Similar letters of reference indicate corresponding parts.

My invention has for its object to furnish an improved washing-machine, simple in construction, convenient in use, and effective in operation, washing the clothes quickly and thoroughly, and without injuring them; and it consists in the combination of the pairs of grooved rollers and their metallic bearings, and the stationary grooved bars with the grooved ends of the tub, and in the combination of the ring rods or wires with the cross-bar, coiled springs, and oscillating rubber, as hereinafter more fully described.

The sides and bottom of the tub are made of a sheet, A, of zinc or other suitable sheet metal, the end edges of which are bent over the curved edges of the lower parts of the vertical ends B. The upper or side edges of the sheet metal A are secured to bars C attached to the lower edges of the upper side parts of the ends B, which project beyond the curved sides to enlarge the upper part of the tub. D are side boards, which are attached to the edges of the bars C and ends B, as shown in Figs. 1 and 2. To the bar C, at one side of the tub, is attached a board, E, to serve as a shelf, and also to prevent the water from spattering out. To the other bar C is attached an ordinary rubbing-board, F, to enable such parts of the clothes as may be very much soiled to be rubbed by hand. In the inner surface of the ends B, parallel with and at a little distance from the sheet-metal plate A, is formed a groove, which, at the side of the tub next the rubber-board F, extends up to the upper edge of the said ends B, as shown in Figs. 1 and 2. G are rollers,

which are made in the form of cylinders, with four longitudinal grooves formed in them, as shown in Figs. 2 and 3. The rollers G are pivoted, in pairs, to metallic blocks or bearings H so formed that they may be slid into the grooves of the ends B. I are bars, the faces of which have two longitudinal grooves formed in them, as shown in Figs. 2 and 4. The ends of the bars I or tenons formed upon said ends are so formed as to be slid into the grooves of the ends B. The stationary rubbing-bars I are alternated with the pairs of rollers G, as shown in Fig. 2. J are the end plates or boards of the oscillating rubber, which are made in about the form shown in Fig. 2, and are connected and held in their proper relative positions by two cross-bars, K. L are cross-bars, the faces of which are grooved or concaved longitudinally, as shown in Fig. 2, and their ends are secured in notches in the curved edges of the plates J. To the outer sides of the plates J, below the centers of the circles of their curved edges, are attached pivots M, which enter vertical grooves in the inner surfaces of the ends B so that the rubber may move up and down to adjust itself to the thickness of clothes being operated upon. This arrangement of the pivots M causes the rubber as it oscillates to turn the clothes completely over at each stroke. The rubber is oscillated by the handle N, which passes down through and is secured to the centers of the cross-bars K. O is a cross-bar, through the center of which the upper part of the handle N passes. To the lower side of the end parts of the cross-bar O are attached the upper ends of the coiled-wire springs P, the lower ends of which are attached to the end parts of the upper bar K. To the ends of the cross-bar O are attached pins or other catches to receive the ring rod or wire Q, or an eye formed upon or attached to said ring Q. The rings Q are pivoted to the ends B below the lower ends of the vertical grooves in which the pivots M work. The rings Q thus hold the bar O against the pressure of the springs P as they are compressed by the clothes being operated upon.

Having thus described my invention, I claim as new and desire to secure by Letters Patent—

1. The combination of the pairs of grooved rollers G and their metallic bearings H and the stationary grooved bars I with the grooved ends B of the tub, substantially as herein shown and described, and for the purpose set forth.

2. The combination of the ring rods or wires Q with the cross-bar O, springs P, and oscil-

lating rubber J K L, substantially as herein shown and described, and for the purpose set forth.

GEO. SEYMOUR.
